BENCH FOR AN ORGAN CONSOLE

Robert L. Eby, 1325 E. Altadena Drive, Altadena, Calif.

Filed July 13, 1964, Ser. No. 80,840

Term of patent 14 years

(Cl. D15—8)

The figure is a perspective view of a bench for an organ console showing my new design. The side and end not shown are the same in appearance as the side and end shown.

I claim:

The ornamental design for a bench for an organ console, as shown and described.
